CLAIM

I claim the ornamental design for a flight simulator, substantially as shown and described.

DESCRIPTION

FIG. 01 is a front perspective view of the flight simulator in accordance with the present design.

FIG. 02 is a back perspective view of the flight simulator.

FIG. 03 is a front view of the flight simulator.

FIG. 04 is a back view of the flight simulator.

FIG. 05 is a top view of the flight simulator.

FIG. 06 is a bottom view of the flight simulator.

FIG. 07 is a left view of the flight simulator.

FIG. 08 is a right view of the flight simulator.

The broken lines shown are included for the purpose of illustrating unclaimed subject matter and forms no part of the claimed design.

The main feature and design of this flight simulator is to allow full 360 degree rotation on all its 3 axis along with movement for Surge, Sway and Heave on those axis.
